ELECTRIC-LAMP SOCKET.

1,160,063.

Specification of Letters Patent.

Patented Nov. 9, 1915.

Application filed February 23, 1915. Serial No. 9,910.

To all whom it may concern:

Be it known that we, FREDERIC P. GATES and GEORGE A. GAUTHIER, both citizens of the United States of America, and both residing at Hartford, in the county of Hartford and State of Connecticut, have invented a certain new and useful Improvement in Electric-Lamp Sockets, of which the following is a specification.

10 Our invention relates to electric lamp sockets and particularly to lock sockets, the object of our invention being to provide a socket having the improvements hereinafter described and shown in the accompanying drawings in which,

Figure 1 is a broken vertical section through a lamp socket in which our invention is embodied in illustrative form; Fig. 2 is a partial vertical section showing the screw plug in its innermost position; Fig. 3 is a partial vertical section showing the end of the key in position to engage the locking screw to retract the latter; Fig. 4 is a detached perspective of portion of the socket shell and the detachable thimble which carries the locking screw; Fig. 5 is a partial section showing the base flange of the thimble in adjusted position in the shell and a partial broken section of the insulating lining as the latter is being adjusted in the shell; and Fig. 6 is a perspective of the locking plate.

The locking socket here shown is of the general type disclosed in the patent to Nero 35 1,131,541 March 9, 1915. It comprises, as in that construction, a casing having a cap 10 and shell 11 within which the insulating body 12 of the socket is supported. The usual lamp terminals are carried by the latter, only the shell terminal 13 being here shown, insulated by the lining 14 from the surrounding casing. At the point 15 the shell 13 is apertured to permit the passage therethrough of the locking plate 16, the 40 free end of which lies in register with the hole 15 in the screw shell. In the present construction the locking plate 16 is provided with a foot piece underlying the base of the shell 13 and secured in position by

the usual securing screw 18 for the lamp shell, which screw passes upward through the perforation in the foot 17 and engages the reinforcing yoke piece 19 which overlies the base flange of the screw shell thus clamping the several parts together. The foot 17 is preferably seated in a shallow recess 20 in the porcelain, the sides of the foot 17 engaging the sides of the recess and thus being restrained from any tendency to swivel which may result from the engagement of the free end of the locking plate with the inserted base 21 of a lamp as the latter is screwed into or unscrewed from inserted position. To engage the lamp base and afford a firm grip thereon, the free end of the locking plate 16 is preferably provided with inwardly struck wings 22. The edges of these are made relatively keen by imparting a bevel to the punch by means of which the locking plate is struck from its blank, with the result that a blank is drawn at the two edges 22 before it is cut. The sharp edge of the die cuts through the metal at an angle to the surface of the latter, thus producing keen edges for the wings 22.

In the construction heretofore employed, the screw plunger 23 is threaded into a thimble soldered permanently to the shell 11 of the casing. It sometimes happens however that the casing 11 must be refinished and this becomes a difficult matter where the thimble is rigid with the casing since it interferes with the burnishing operation as the casing is spun. To avoid this difficulty, the present thimble 24 is made readily detachable from the casing and is held in place only by the pressure of the insulating lining 14 against the base flange 25 of the thimble. The latter is held against rotation by a hexagonal shoulder 26 formed thereon adjacent the base flange 25 and taking into a corresponding hexagonal aperture 27 in the casing 11. Obviously it is only necessary to pass the thimble 24 up within the interior of the shell 11 and then force it radially outward through the aperture 27 therein until the latter is engaged by the hexagonal shoulder 26, to assemble the thimble on the

5 casing. The insertion of the insulating lining 14 which fits snugly within the shell 11, prevents the thimble from becoming loose and holds the hexagonal shoulder 26 in engagement with the aperture 27 in the shell. Obviously it is only necessary to press the thimble inward, after the lining 14 has been removed in order to remove it and thus prepare the casing for refinishing. To facilitate the introduction of the lining 14, the base flange 25 of the thimble is extended upward to form a tongue 28 which is outwardly flared to overlie the shoulder 29 of the shell. The outer end of the lining 14 being of less diameter than the shell above the shoulder 29, it engages on the rounded inner face of the tongue 28 and slides down freely within the flange 25 without danger of catching on the edge of the latter and 20 pulling the thimble out of the hole 27 in the casing.

In the prior Nero construction it was possible to screw the plug 23 in by means of its key until it had escaped the threads of the thimble 24. This not only resulted in the inconvenience through the separation of the parts, but also in injury to the locking plate since the latter was thereby bent to such an extent that it did not return under its own resiliency to its normal position. These troubles have now been obviated by providing the key 30 with the stud 31, carrying a pin 32 which engages in a cam slot 33 in the shell of the key. When the key is turned 35 to the right to screw the plug 23 inward, the stud 31 which engages the screw 23 is retracted by the pin 32 until only a sufficient length thereof protrudes beyond the shell 30 to permit the screw 23 to be turned in a 40 suitable distance to move the locking plate 16 into firm engagement with the base 21 of the lamp. When the screw 23 has reached this position, a further rotation of the key merely results in the withdrawal of 45 the head 34 of the screw from its socket 35 in the stud 31, by reason of the engagement of the shell of the key 30 with the end of the thimble 24 and the engagement between the key and the screw is thus broken. In 50 order to withdraw the screw 23, the key 30 is rotated in the opposite direction with the result that the stud 31 is extruded by the running of the pin 32 into the outer end of the slot 33. Consequently the lengthened 55 stud 31 may be passed in to the thimble 24 a sufficient distance to again bring the socket 35 into engagement with the head 34 of the screw. Further reverse rotation of the key results in the withdrawal of the 60 screw 23 in the usual manner.

It is obvious that with the present construction it is impossible to rotate screw 23 inwardly beyond the predetermined distance at which its engagement with the op-

erating key is broken. Nevertheless, the 65 same key may be employed to withdraw the screw 23 by reason of the extension of the stud element 31 on the reverse rotation of the key.

The construction shown may be modified 70 in various ways without departing from what we claim as our invention.

We claim:—

1. An electric lamp socket having a casing comprising a shell provided with a non-circular aperture, an internally threaded thimble provided with a base flange and having adjacent the latter a non-circular portion adapted to fit within the aperture in the casing shell, together with an insulating lining for said casing bearing upon the base flange of said thimble to hold the latter in assembled position with relation to the shell. 80

2. An electric lamp socket having a casing comprising a shell having intermediate its ends a shoulder 29, and apertured adjacent its lamp-receiving end, in combination with an internally threaded thimble adapted to be seated in said aperture and having a base flange lying within said shell, said flange having an outwardly flared extension 28 overlying said shoulder 29 in the assembled position of the parts, together with an insulating lining for said casing serving 95 to hold said thimble in assembled position in the shell.

3. In a lamp socket, an apertured screw shell, a locking plate having its free end in register with the aperture in said screw shell, a thimble carried by the socket casing, a screw threaded into said thimble in register with the free end of said locking plate, together with a key for advancing said screw through its thimble, and means 100 for breaking the operating connection between said key and screw after the latter has been advanced a predetermined distance. 105

4. In a lamp socket, an apertured screw shell, a locking plate having its free end in register with the aperture in said screw shell, a thimble carried by the socket casing, a screw threaded into said thimble in register with the free end of said locking plate, together with a key for advancing 110 said screw through its thimble, and means for breaking the operating connection between said key and screw after the latter has been advanced a predetermined distance, together with means operative to reestablish 115 the engagement between said key and screw upon the reverse rotation of the key to withdraw said screw. 120

5. An electric lamp socket comprising a casing, a thimble carried thereby and a screw threaded into said thimble and projecting into the interior of the casing to actuate a locking bar, in combination with a 125

key comprising a shell and a stud member working within said shell, together with a cam engagement between said stud and shell for retracting said stud on the rotation of the key in one direction, and for advancing the stud on the rotation of the key in the opposite direction, for the purpose described.

In testimony whereof we have signed our

names to this specification, in the presence of two subscribing witnesses.
